UNITED STATES PATENT OFFICE.

CHARLES KRAUSS, OF NEWARK, NEW JERSEY.

DESIGN FOR A FINGER-RING.

SPECIFICATION forming part of Design No. 12,577, dated November 22, 1881.

Application filed October 10, 1881. Term of patent 3½ years.

To all whom it may concern:

Be it known that I, CHARLES KRAUSS, a citizen of the United States, residing at Newark, in the county of Essex and State of New Jersey, have invented and produced a new and original Design for Finger-Rings, of which the following is a specification, reference being had to the accompanying drawings, forming part thereof.

Figure 1 represents a front view of the shank of the ring. *a* designates holes, which may be round, cut at different places into each side of the shank of the ring. Said holes are arranged in groups, substantially as shown, which groups are at equal distances on each side of the stone or cameo ornamenting the ring, and about halfway down the shank. *b* designates bars of gold slightly curved, set in a slightly divergent position at equal distance apart, and being about of equal size and shape. The one end of each of said bars is set into each one of said holes, partly filling the same and leaving in the shank a small open semicircular aperture. The other ends of said bars compose the set-

ting and hold the stone or cameo with which the ring is ornamented. *c* is a fine cross-bar of about the same thickness as the aforesaid bars, and set crosswise over the same, near said holes in the shank, for ornament and finish, said cross-bar being engraved or otherwise ornamented. The number of bars and holes forming the ornament for the shank of the ring may be increased or decreased according to the width and weight of the ring.

Fig. 2 represents a side view of the ring. 35

I claim—

The design for a finger-ring herein shown and described, the shank of which is ornamented with a number of small holes in groups and a number of curved bars, the ends of the latter being set into the aforesaid holes in the shank of the ring, the other end being adjacent to the stone or cameo ornamenting the ring, substantially as herein set forth.

CHARLES KRAUSS.
